COMBINED CLOCK AND CURIO CABINET

Leonard Eisen, 14 Lomas Lane, Montvale, N.J. 07645

Filed July 23, 1974, Ser. No. 491,122

Term of patent 14 years

Int. Cl. D10—01

U.S. Cl. D10—2

FIG. 1

FIG. 2

FIG. 1 is a left side elevational view of a combined clock and curio cabinet showing my new design; and

FIG. 2 is a right front perspective view thereof, the rear, not seen being plain and unornamented.

I claim:

The ornamental design for a combined clock and curio cabinet, as shown and described.
